METHOD FOR DYEING TEXTILE MATERIALS
WITH VAT DYES

Gilbert S. Panson and Carol E. Weill, Livingston, N.J.,

Mass., a corporation of Massachusetts
No Drawing. Filed July 17, 1961, Ser. No. 124,373
6 Claims. (Cl. 8—34)

This invention relates to dyeing textile materials with
vat dyes.

Textile materials, such as cotton fabrics, usually are
dyed by padding a vat dye on to the fabric, squeezing
out the excess, and then passing the dye impregnated
fabric through an aqueous bath containing sodium hy-
droxide, sodium hydrosulfite and sodium chloride. The
reducing liquor reduces the dye and converts it to the
water soluble sodium leuco form, the presence of the salt
shifting the equilibrium of the reduced dye from the solu-
tion to the fabric. The cloth then is removed from the
bath and the dye oxidized to give a level dyeing of de-
sired shade. This procedure requires the use of as much
as 5 to 40 fold excess of hydrosulfite over the stoichio-
metric requirement since the hydrosulfite is very unstable
under the conditions of air oxidation present in dyeing
and the high temperatures used in the dyeing operation.

It has been proposed heretofore that an alkali metal
bisulfite, such as sodium bisulfite, can be converted to
alkali metal hydrosulfite in an aqueous medium by the
addition of an alkali metal borohydride, such as sodium
or potassium borohydride. Thereafter, an alkali metal
hydroxide may be added and the resulting alkaline solution
may be used for reducing vat dyes and for dyeing
textile fabrics by immersing the textile fabric in the al-
kaline hydrosulfite solution. This procedure does not
solve the instability problem of the hydrosulfite and re-
quires the substantial absence of alkaline metal hydroxide
during the reaction between the alkali metal bisulfite and
alkali metal borohydride.

The present invention is based upon the discovery that
if a textile fabric is impregnated with a mixture of a
vat dye and an alkali metal bisulfite and the thus im-
pregnated fabric is passed through a reducing liquor con-
sisting of an aqueous solution of an alkali metal hy-
droxide and an alkali metal borohydride having a pH
between about 9.5 and 13, the vat dye is reduced and
converted to its water soluble alkali leuco form. Thus,
in accordance with the method of the present invention,
a mixture of a vat dye and an alkali metal bisulfite, such
as sodium bisulfite, in the form of an aqueous dispersion
is padded on to the textile fabric, the excess being
squeezed out. The thus impregnated fabric then is passed
through an aqueous reducing solution consisting essen-
tially of an alkali metal hydroxide, such as sodium hy-
droxide, an alkali metal borohydride, such as sodium or
potassium borohydride, and a salt, such as sodium chlo-
ride. The fabric then is removed from the reducing
solution and subjected to an oxidizing operation.

Since the composition of the various vat dyes varies, the
amounts of alkali metal bisulfite and alkali metal bor-
ohydride required in the practice of the invention will
vary. In general, about 4 to 400 parts by weight of
alkali metal bisulfite and about 0.2 to 20 parts by weight
of alkali metal borohydride per 100 parts by weight of
vat dye may be used. The use of greater amounts of
bisulfite and borohydride are not harmful. It will be
understood that in a continuous dyeing operation, the
concentration of alkali metal hydroxide, alkali metal
borohydride, and salt in the reducing bath must be main-
tained sufficiently high and, preferably, substantially con-
stant to effect the desired reduction and obtain level dye-
ing.

2

The amount of sodium hydroxide required in the re-
ducing bath varies with the class of vat dye used and can
be determined from the booklets published by the dye
manufacturer. Each dye works best at a certain sodium
hydroxide level. Sufficient sodium hydroxide in ex-
cess of the amount required to convert the dye to its
alkali leuco form must be present to stabilize the bath.

In some instances in commercial operation it is desira-
ble to dry the impregnated fabric before immersion in
the reducing bath. Cloth impregnated with vat dye and
sodium bisulfite in accordance with the invention can be
dried at 110° C. for 1 to 2 hours and then immersed
in the reducing bath and obtain the desired shade. This
indicates the great stability of the mixture of bisulfite
and vat dye.

Reduction of the dye to the sodium leuco and ex-
haustion of the dye in to the fabric is dependent upon the
temperature of the bath and the time of contact. At
high temperatures, such as 80° C. and higher, the con-
tact time is less than 10 seconds which makes the inven-
tion particularly useful for continuous dyeing, such as
in the Williams unit. At lower temperatures, longer con-
tact times are needed to insure full reduction and pene-
tration of the dye. The latter conditions are more useful
in the Beck dyeing operations or package dyeing opera-
tions where longer contact times are needed.

The mixture of alkali metal bisulfite and vat dye used
in the practice of the invention is completely stable and
can be stored for long periods of time. The aqueous sol-
ution of alkali metal hydroxide and alkali metal borohy-
dride is available in concentrations which also are ex-
tremely stable even at high temperatures for long periods
of time. When the fabric impregnated with the mix-
ture of alkali metal bisulfite and vat dye is passed into
the reducing solution, the vat dye is reduced and con-
verted to its water soluble alkali leuco form in a very
few seconds. Consequently, the residence time required
in the reducing bath is very short and there is very little
opportunity for the side reaction of air oxidation to occur.
This is of particular industrial significance because
it makes possible vatting operations with substantially less
reducing agent than has heretofore been required.

While we have described the use of the alkali metal
borohydrides in the practice of the invention, the quater-
nary ammonium borohydrides may be used in place
thereof if desired. As illustrative of water soluble qua-
ternary ammonium borohydrides we may mention the
lower tetraalkyl ammonium borohydrides, such as tetra-
methyl, tetraethyl, trimethyl ethyl, dimethyl diethyl am-
monium borohydrides, as well as quaternary ammonium
borohydrides responding to the formula $R_x(CH_3)_yNBH_4$
where R is a saturated or unsaturated straight chain
aliphatic hydrocarbon radical containing about 7 to 21
carbon atoms, x and y are integers from 1 to 3, and x
plus y equals 4, such as tricapryl methyl ammonium
borohydride, cetyl trimethyl ammonium borohydride, etc.

We have successfully used in the practice of the inven-
tion many vat dyes selected from the various types com-
monly used in commercial practice. As illustrative of
such vat dyes we may mention anthraquinone type dyes,
such as Mayvat Jade Green (C.I. #59,105), Carbanthrene
Blue BCS (C.I. #69,825), Ponsul Brilliant Violet 4RN
(C.I. #60,010), Ponsul Golden Orange 3G (C.I.
#69,025), Indanthrene Golden Yellow RK (Vat Orange
1, C.I. #59,105/6), Indanthrene Brilliant Orange RK
(Vat Orange 3, C.I. #59,300), Amanthrene Golden
Orange F (Vat Orange 9, C.I. #59,700), Indanthrene
Orange RRT (Vat Orange 1, C.I. #59,705), and Indan-
threne Dark Blue BO (Vat Blue 20, C.I. #59,800),
Tinon Navy Blue RAF (Vat Blue 18, C.I. #59,815),
Ahcovat Jade Green B (Vat Green 1, C.I. #59,825),
Indanthrene Brilliant Violet 3B (Vat Violet 9, C.I.

#60,005), Cibanone Violet 4R (Vat Violet 1, C.I. #60,010); anthraquinone type dyes containing amino groups, such as Cibanone Black DRB (Vat Black 9, C.I. #65,230); dyes containing a heterocyclic nucleus fixed to a central vatting system, such as Indanthrene Red FBB (Vat Red 10, C.I. #67,000), Tinon Yellow GC (Vat Yellow 2, C.I. #67,300), Carbanthrene Red BN (Vat Red 35, C.I. #68,000), Cibanone Violet BNA (Vat Violet 13, C.I. #68,700), Indanthrene Brown RN (Vat Brown 3, C.I. #69,015), Indanthrene Red Brown 5 RF (Vat Brown 25, C.I. #69,020), Tinon Olive BF (Vat Green 3, C.I. #69,500), Tinon Olive SF (Vat Black 25, C.I. #69,525), Cibanone Blue GCDN (Vat Blue 14, C.I. #68,810), Ponsul Blue BF (Vat Blue 6, C.I. #69,825), Indanthrene Khaki GG (Vat Green 8, C.I. #71,050); indigo and its derivatives and homologues, such as Cibanone Blue 2BGD (Vat Blue 5, C.I. #73,065); thio-indigo and its derivatives and homologues, such as Hostavat Brilliant Pink R (Vat Red 1, C.I. #73,360), Indanthrene Printing Violet 6R (Vat Violet 3, C.I. #73,395); phthalocyanine dyes, such as Algol Brilliant Blue 4G (Vat Blue 29, C.I. #74,140).

The invention is illustrated further by the following specific examples, the results of which are shown in the following tables. In all of these examples level dyeings to the shade specified by the dye manufacturer were obtained. In these tables the term "reduced" indicates proper sodium leuco was formed and samples of cloth dyed gave the color and shade indicated by the dye manufacturer.

In the following tables the following formulations were used as standard unless otherwise indicated in the table.

PAD BATH

4.0 grams of vat dye (as a single paste) was diluted with 125.0 grams of water and 8.3 grams of sodium bisulfite was stirred into the diluted paste. Variable amounts of water or dye can be used depending upon the final shade desired. Cotton cloth was immersed in this mixture and then passed through squeeze rolls to remove the excess.

REDUCING BATH

The standard reducing bath contained 0.2 gram of sodium hydroxide, 0.4 gram of sodium borohydride, 20 grams of sodium chloride and 250 grams of water. The bath was heated to 80° C. The cloth from the squeeze rolls was passed into the reducing bath where reduction took place rapidly. The cloth then was removed and subjected to a conventional oxidizing operation.

Table I

Example	Dye Used	Temp. (° C.)	pH	Contact Time	Comment
1.....	Vat Red 1, (C.I. #73,360)	80	11.3	5 sec....	Reduced.
2.....	Vat Red 29, (C.I. #71,140)	80	11.3	5 sec....	Do.
3.....	Vat Orange 5, (C.I. #73,335)	80	11.3	5 sec....	Do.
4.....	Vat Yellow 2, (C.I. #67,300)	80	11.3	5 sec....	Do.
5.....	Vat Yellow 4, (C.I. #59,100)	80	11.3	5 sec....	Do.
6.....	Vat Green 1, (C.I. #59,825)	24	11.45	5 min....	Partially reduced.
7.....	do.....	80	11.3	5 sec....	Reduced.
8.....	do.....	Boil	11.25	1 sec....	Do.
9.....	Vat Blue 5, (C.I. #73,065)	80	11.3	5 sec....	Do.
10.....	Vat Blue 6, (C.I. #69,825)	80	11.3	1 sec....	Do.
11.....	Vat Blue 20, (C.I. #59,800)	80	11.3	5 sec....	Do.
12.....	Vat Blue 43, (C.I. #53,630)	80	11.3	5 sec....	Do.
13.....	Vat Violet 3, (C.I. #73,396)	80	11.3	5 sec....	Do.
14.....	Vat Black 25, (C.I. #69,525)	80	11.3	5 sec....	Do.

The pH indicated is that at the temperature shown in the table before immersing the impregnated cloth.

Table II

5 This table illustrates the effect of the ratio of dye to sodium bisulfite, the dye used being Vat Green 1 (C.I. #73,360).

Example	Dye in grams	NaHSO ₃ in grams	Ratio of dye to NaHSO ₃	pH	Comment
19.....	15.0	0.5	30.0	11.3	Reduction incomplete.
20.....	20.0	1.0	20.0	11.3	Reduced.
21.....	10.0	1.0	10.0	11.3	Do.
22.....	15.0	8.3	1.8	11.3	Do.
23.....	4.0	8.3	0.48	11.3	Do.
24.....	4.0	12.0	0.33	11.3	Do.

The pH is that at the temperature of 80° C. before immersing the impregnated cloth.

Table III

25 This table illustrates the effect of the ratio of sodium bisulfite to sodium borohydride, the dye used being Vat Green 1 (C.I. #73,360).

Example	NaHSO ₃ in grams	NaBH ₄ in grams	Ratio of NaHSO ₃ to NaBH ₄	pH	Comment
25.....	8.3	0.4	20.75	11.3	Reduced.
26.....	12.0	0.1	120.0	9.6	Do.
27.....	0.5	0.4	1.25	11.9	Do.
28.....	8.3	8.7	0.95	12 ⁺	Do.

35 The pH indicated is that at a temperature of 80° C. before immersing the impregnated cloth.

We claim:

1. In a method for continuously dyeing textile materials with vat dyes which involves padding the textile material with an aqueous dispersion of the vat dye and passing the dye impregnated textile material through an aqueous solution of a vat dye reducing agent, the improvement wherein the textile material is impregnated with a mixture of the vat dye and an alkali metal bisulfite and the textile material impregnated with the vat dye and bisulfite is passed through an aqueous solution of a borohydride and an alkali metal hydroxide having a pH between about 9.5 and 13, said borohydride being selected from the group consisting of alkali metal borohydrides and quaternary ammonium borohydrides.

2. The method as claimed by claim 1 wherein the borohydride is an alkali metal borohydride.

3. The method as claimed by claim 1 wherein the borohydride is a water soluble quaternary ammonium borohydride.

4. The method as claimed by claim 1 wherein the alkali metal bisulfite is sodium bisulfite.

5. The method as claimed by claim 2 wherein the alkali metal borohydride is sodium borohydride.

6. The method as claimed by claim 4 wherein the borohydride is sodium borohydride.
